[57] ABSTRACT

A machine for making a partly woven and partly knitted fabric, having a row of lapping guides mounted on a crossbar for simultaneous angular movement about parallel axes and having radial arms provided with eyelets threaded with weft threads supplied from a weft supply beam and moving along part-circular paths within open warp sheds between an initial position projecting in warp direction, and one, or two opposite, lapping end positions for laying the weft threads into the opened hooks of knitting needles so that knitted stitch wales are formed of sectional weft thread loops between fabric portions woven of warp threads and the sectional weft thread loops.

MACHINE FOR MAKING A PARTLY WOVEN AND PARTLY KNITTED FABRIC

BACKGROUND OF THE INVENTION

The present invention relates to a machine for manufacturing a partly woven and partly knitted textile fabric. A machine serving this purpose is disclosed in the U.S. Pat. No. 3,580,295 in which a knitting mechanism is provided for inserting weft threads into an open warp shed, constituted by an array of lapping guides. The weft threads are taken off a stationary package in the form of hairpin-like weft thread loops. The lapping guides are mounted for oscillation on a support bar and provided with eyelets reciprocating along parallel paths extending from an outer end position outside of the warp shed obliquely between the warp threads of the upper warp into the open shed. Each lapping guide is associated with a knitting needle which catches the weft threads and interlaces the respective weft thread loops to form a stitch wale located between two adjacent warp thread groups interlaced with stitch connecting loops of the weft threads to form woven fabric portions. The hooks of the knitting needles are displaced to an operative position in the open shed out of an initial position in front of the fell and beat up plane of the fabric. The stitch connecting weft loops are beaten up by a conventional reed into the fell of the fabric which is wound up by a take-up beam.

A disadvantage of the prior art machine resides in that, as the weft threads are inserted into the shed from the outside, small spots are formed at the points where the lapping guides penetrate, and such spots are noticeable in the finished fabric as undesirable strips in the warp direction. Since the lapping guides are inserted into the open warp shed from outside, the warp is excessively stressed at the lapping guide penetrating points, and on the other hand, faults in the woven fabric may appear, since the lapping guides do not penetrate the upper warp always at the same points. Furthermore, the location of the lapping guides above the weaving plane of the fabric which is being made, has the disadvantage that the operator of the machine has no access to the warps in the region between the fell of the fabric and the reed.

An other machine is known which is also designed for making a partly woven and partly knitted fabric, wherein the weft threads, of which a warp knit structure is formed are threaded into the heddles of an auxiliary independently controlled heddle frame harness. No lapping guides are provided, which are replaced by a transversely movable reed in which both warp and weft threads are threaded, each in one dent space of the reed which can be moved from an intermediate initial position in which the warp threads are straight and parallel, to one of two lapping end positions and back again, while at the next shed change, the reed is moved into the opposite lapping end position, and back again. Since the reed is moved transversely from the intermediate initial position to one of the lapping end positions, the weft threads are placed in positions above or below the respective knitting needles, and laid into the needle hook by the movement of the auxiliary harness. After the weft threads have been lapped into the respective needle hooks, the reed is returned from one of its lapping end positions to the intermediate initial position in which the stitch connecting weft loops are beaten up by the reed against the fell of the fabric. After the beat up

operation and the change of the warp shed, the reed is moved to the other opposite lapping end position and back again to the initial position. New stitch loops are drawn in the beat up plane of the reed through old stitch loops formed in the preceding warp shed, and the double stitch connecting loops extending across the warp between each adjacent pair of knitting needles, are beaten up by the reed within the beat up plane of the fabric which is being made, and interlaced with the warp threads to form a woven fabric portion.

Due to the alternate transverse reciprocation of the reed, the weft threads are lapped onto the knitting needles to form a warp knit tricot or cloth binding structure. It is not possible to make an atlas binding structure due to the return of the reed to its initial position before the beat up.

It is a disadvantage of the machine according to the prior art that the knitting mechanism uses knitting needles, the reed, and an auxiliary harness to perform the function of lapping guides. In order to obtain a perfect performance of the mechanism, it is necessary to use a warp shed which can be formed by imparting a high tension to the warp threads. Therefore, it is a disadvantage of the prior art machine that during the lapping operation by which the weft threads are placed in the needle hooks, the warp threads are also tensioned due to the transverse reed movement while the fabric is held in the beat up plane only by the stitches caught by the knitting needles.

The transverse movement of the reed, together with both warp threads and weft threads, takes place in the open warp shed, and the warp threads may be exposed to a maximum tension between 100 and 150 kg/m of fabric width.

Another disadvantage of the prior art machine is the inconvenient location of the auxiliary harness between the rear dead center position of the reed and the auxiliary harness whereby the distance between the beat up plane of the fabric and the auxiliary harness is undesirably extended which results in the necessity of making a larger warp shed opening in the plane of the auxiliary harness. Another factor, which should not be overlooked, is the fact that the lapping is insufficiently reliable due to the movements of the auxiliary harness whose heddles control the weft threads when they are laid into the hooks of the knitting needles. Since the reed is located between the heddle eye and the hook of the knitting needle, the reliability of the lapping is unfavorably influenced since the threads rub against the reed dents, which is very undesirable, particularly when certain yarn types are being used.

SUMMARY OF THE INVENTION

It is an object of the invention to provide a machine for making a partly woven and partly knitted fabric with a knitting mechanism which substantially eliminates the disadvantages of the prior art, and which is particularly suitable for high speed weaving operations.

This object is obtained by machine for manufacturing a partly woven and partly knitted textile fabric, comprising means for forming warp sheds, a knitting mechanism for forming a warp structure having stitch wales located between adjacent groups of warp threads interlaced to form a weave with stitch connecting weft thread loops, and means for beating up the stitch connecting loops into the fell of the fabric. The knitting mechanism comprises a lapping guide mechanism

threaded with weft threads taken off a stationary pack-
age, and on the other hand, a system of knitting needles
with closable hooks disposed in a row extending across
the fabric being made for catching lapped weft threads
and for forming stitch wales of the caught weft threads.
In accordance with the invention, the lapping guide
mechanism is formed of lapping guides which are sup-
ported in a cross-bar and which have arms terminating
in weft thread guiding eyelets, and which are oscillated
along coextensive paths in the form of circular arcs
within each open warp shed from an intermediate ini-
tial position, in which a perpendicular projections of
the lapping guide arms onto the plane of the warp
threads in the closed shed position, are parallel with the
warp threads, into a lapping end position and back
again, whereupon in the next open warp shed, the lap-
ping guide arms move either to the same lapping end
position as before, or in the opposite direction to an-
other lapping end position, and back again. The lapping
guides penetrate in the closed shed position, the plane
of the warp threads, and in the open shed position, at
least one of the two planes in which the warps are lo-
cated when the shed is opened.

A mechanism is provided in the crossbar which sup-
ports the lapping guides for imparting an oscillating
movement to the lapping guides. Each lapping guide
has a stem with a journal portion mounted in a bearing
bore of the crossbar so that the respective lapping
guide can oscillate about an axis with its lapping arm.
Means are provided in the crossbar for imparting an os-
cillation movement to the lapping guides. In one em-
bodiment of a lapping guide, the lapping arm has two
separate portions radially extending from the stem of
the lapping guide, and converging toward an apex pro-
vided with the thread guiding eyelet.

The knitting mechanisms of the invention has two
main embodiments. In a first embodiment, the crossbar
supporting the lapping guides is stationary, while in the
second embodiment, the crossbar is mounted on the
sley and moves with the same.

In one embodiment, the stationary crossbar is ar-
ranged under the warp in the region between the hed-
dle frames and the fell of the fabric, while in another
embodiment, the stationary crossbar with the lapping
guides is arranged under a flat stationary support defin-
ing the beat up plane of the fabric.

When a stationary crossbar is used, the axes of oscil-
lations of the lapping guides are either substantially
perpendicular, or slanted to the weaving plane formed
by warp threads in the closed shed position.

In the embodiment with a movable crossbar support-
ing the lapping guides, the oscillation axes of the lap-
ping guides in the rear dead center position of the sley,
can be either parallel with, or perpendicular to the
plane of the warp threads in the closed shed position.
It is also possible to mount the lapping guides for move-
ment about oscillation axes extending in the rear dead
center position of the sley, parallel with the plane of the
lower warp in the open warp shed position, or concur-
rent to the plane of the warp threads in the closed warp
shed position.

In the intermediate initial position of the lapping
guides, the thread guiding eyelets of the lapping arms
thereof can point substantially either toward the beat
up plane of the fabric, or toward the harness.

If a stationary crossbar is provided, and lapping
guides are used whose lapping arms with eyelets point

in the intermediate initial positions of the lapping
guides substantially toward the beat up plane of the
fabric, the lapping guides pass in the rear dead center
position of the sley through dent spaces of the reed,
whereas they do not pass through the same in the for-
ward beat up position of the sley. On the contrary in the
case of lapping guides on a stationary crossbar whose
lapping arms point in the intermediate initial position
of the lapping guides toward the harness, the lapping
guides pass in the foremost dead center position of the
sley through dent spaces of the reed, whereas in the
rear dead center position of the sley, they do not pass
therethrough.

When a stationary crossbar is used, a conventional
reed is provided on the sley, which beats the stitch con-
necting loops into the fell of the fabric.

On the other hand, when the crossbar is mounted on
the sley for movement therewith, the lapping arms of
the lapping guides mounted on the crossbar serve to
beat up stitch connecting loops into the fell of the fab-
ric in the foremost sley position.

In the above-described two mechanisms, the knitting
needles and lapping guides can be aligned, respectively,
or staggered. If each lapping guide is aligned with a
knitting needle in the intermediate initial position of
the lapping guide, the arm of the lapping guide points
toward the corresponding knitting needle, whereas in
the event that the knitting needles and lapping guides
are not aligned, respectively, the lapping arms are dis-
posed in staggered positions relative to the knitting
needles.

When the lapping guides and needles are respectively
aligned, and the weft threads are lapped by the eyelets
of the lapping arms to the knitting needles from the in-
termediate position alternately to two opposite lapping
end positions, the lapping guides form a clothwarp knit
structure, whereas in the embodiment in which the lap-
ping guides are oscillated in opposite directions to a
single lapping end position from the intermediate initial
position, a warp knit structure is formed as described
in the U.S. Pat. No. 3,580,295. If the needles and lap-
ping guides are staggered, and the weft threads are
lapped onto the knitting needles alternately in two op-
posite lapping end positions, the lapping guides form a
tricot warp knit structure, whereas in the embodiment
in which the lapping guide swings from the initial posi-
tion repeatedly to the same lateral lapping end position,
a warp knit structure is formed which is also described
in the U.S. Pat. No. 3,580,295.

A lapping guide can be made of a metal blank bent
of a flat piece of wire, with a weft thread guiding eyelet
formed by a hole provided in the wire at the apex of the
lapping arm, or the lapping guide may be stamped out
of a metal sheet blank.

When a reed is provided in the machine, it is pre-
ferred to make the movement of the knitting needles
from the starting positions to the operative positions
phase shifted relative to the movement of the reed from
its front beat up position, so that the knitting needles
enter the warp shed prior to the movement of the reed
out of the beat up position.

The knitting needles can be operated so that the
hooks thereof move either around an endless closed
curved path, or reciprocate along a linear path.

The first movement is preferred in arrangements
where the plane of coextensive circular arc paths along
which the eyelets of the lapping guides move, is sub-

stantially parallel with the weaving plane of the warps in the closed shed position, or where, if a movable crossbar is used for the lapping guides, the plane of coextensive circular arc path is substantially parallel with the weaving plane of the warps in the closed shed position, when the sley is in the rear dead center position.

The linear movement of the knitting needles is preferred, if a stationary crossbar is used for supporting the lapping guides, when the plane of coextensive circular arc paths along which the eyelets of the lapping guides move, is concurrent to the plane of the warps in the closed shed position, or, if a movable crossbar is used, when the plane of coextensive circular arc paths is concurrent to the warp plane in the rear dead center position of the sley.

In accordance with another embodiment of the invention, it is possible to use knitting needles whose hooks move around a closed endless curvilinear path, and lapping guides whose plane of coextensive circular arc paths along which the eyelets of the lapping guides move, is in the case of a stationary crossbar, concurrent to the warp plane in the closed shed position, or in the case of a movable crossbar, in the rear dead center position of the sley, is concurrent to the warp plane.

If the arrangement of the present invention is compared with known knitting mechanisms for inserting weft threads into a warp shed, the advantage of the lapping guides according to the invention resides in that the lapping guide arms with weft threads threaded into the eyelets thereof, can oscillate within the warp shed without additionally stressing the warp threads, and furthermore in that the lapping guides separate the warp threads from one another, preventing them from passing into adjacent longitudinal strips of the fabric.

Due to the fact that the weft threads are lapped into the needle hooks by oscillating lapping arms, the entire mechanism is made less complicated as compared with the prior art, and the lapping operation is more reliable, particularly at high operational speeds.

The arrangement of lapping guides supported for angular movement in a crossbar on the sley contributes considerably to the simplicity of the machine, since the arms of the lapping guides can be designed to perform also the function of a reed. This arrangement facilitates the movements of the warp threads, and is therefore convenient, particularly from the point of view of an attendant controlling the machine.

The device for inserting weft threads into the warp shed by means of oscillating lapping guides according to the invention, permits a very easy exchange of cams for controlling the operations for forming different weft and warp binding fabric structures, making possible a greater variety of patterns, and improving the versatility of the machine.

A very simple device is required for oscillating the lapping guides requiring little service and making possible an easy exchange and replacement of machine parts. The simple construction of the lapping guides is highly advantageous inasmuch as it makes possible mass production thereof at a relatively low manufacturing cost.

The weft inserting device according to the invention is capable of handling any type of weft threads made of natural and man-made fibers. Even strips and metallic or glass filaments can be used as material for the weft threads.

The stitches in the wales formed of weft thread loops, can be either open or closed, the spaces in weft direction between stitch connecting weft thread loops being freely variable.

5 The apparatus of the invention also makes it possible to manufacture fabrics consisting of extremely loose weft sets, for example for curtains or decorative fabric in which both warp and weft threads are prevented from slipping, since the stitch connecting weft thread loops are secured at both ends in the wales.

When the weft threads are lapped, due to the reciprocal oscillation movement of the lapping guides, in alternate lapping end positions, and thereafter interlaced with warp threads, the final product has excellent 15 dimensional stability, as compared with warp knitted fabrics.

Unlike in conventional looms, the weaving operations of the machine of the invention are not limited by the width of the fabric to be manufactured, and it is 20 possible to weave one or more stripes of fabric side-by-side without additional selvedge forming devices. Moreover, as compared with some types of shuttleless looms, no waste of weft thread occurs.

25 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is a view illustrating a fabric made on the machine of the invention by alternate weft lapping in opposite directions;

FIGS. 26 and 27 are fragmentary schematic plan views illustrating successive operational positions of a knitting mechanism having lapping guides oscillating alternately in opposite directions, and located in an intermediate initial position staggered to and located between two adjacent knitting needles;

FIG. 28 is a schematic fragmentary plan view illustrating a fabric made by the knitting mechanism illustrated in FIGS. 26 and 27;

FIG. 29 is a schematic plan view illustrating a fabric made by lapping guides lapping in only one direction to a lapping end position out of an initial intermediate position shown in FIG. 31;

FIGS. 30 and 31 are fragmentary schematic plan views illustrating successive operating positions of the knitting mechanism for making the fabric illustrated in FIG. 29;

FIG. 32 is a fragmentary schematic side view, partially in section, illustrating a knitting mechanism with lapping guides mounted on the sley and having oscillation axis which are perpendicular to the warp thread plane in the closed shed position when the sley is in the rear dead center position;

FIG. 33 illustrates a lapping guide for the knitting mechanism of FIG. 32 and being formed of a wire;

FIG. 34 illustrates a lapping guide stamped out of a metal sheet;

FIG. 35 is a fragmentary schematic plan view illustrating the knitting mechanism of FIG. 32;

FIG. 36 is a fragmentary schematic side view illustrating the knitting mechanism of FIG. 32 in the beat up position of the sley; and

FIG. 37 is a fragmentary schematic side view of the knitting mechanism shown in FIG. 4, provided with a knock-over device and illustrating the relation between the movements of the reed and of the knitting needles.

DESCRIPTION OF THE PREFERRED EMBODIMENTS

Referring now to the drawing, and more particularly to FIG. 1, a partly woven and partly knitted fabric is shown which can be made on a weaving machine according to the invention. Weft threads 1 form a warp-knit binding, such as the so-called cloth structure,

which is designed so that the longitudinal stripes 2 are formed of interlaced warp threads 3 together with pairs of parallel connecting loops 4 of stitches 5. Wales 6 are produced by mutually interlaced stitches 5 and located in the gap 7 between the longitudinal stripes 2, the longitudinal direction being the warp direction.

Pairs of connecting loops 4 of stitches 5, which are disposed side-by-side, form a sectional weft 8 comprising stitches 5 which are coextensive but oriented in opposite directions, respectively, to both the preceding and succeeding sectional wefts 8.

The fabric illustrated in FIG. 1 has a secured selvedge as shown at the left side of FIG. 1. The other selvedge is not shown, and is a mirror image of the left-hand selvedge.

The outer stitches 5' of the left marginal longitudinal stripe 2' have the same length as the stitches 5 in the respective gap 7, but are not interlaced with one another to form a wale, but are aligned with the sectional weft 8.

Between the legs of the connecting loops 4 of the stitches 5 in the marginal stripe 2', which legs are connected in the outer stitch 5', there are located the legs of the connecting loops 4' which legs are connected by links 9 with the succeeding and preceding legs of the connecting loops 4', respectively.

The fabric illustrated in FIG. 1 is made on the machine schematically shown in FIG. 2.

Between the lateral frames 11 of the machine, a warp beam 12 is supported from which warp threads 3 are taken off by a rotary back rail 13 and then passed through the heddles of two heddle frames 14 and 15 which form a harness. Upright posts 16 are secured to the side frames 11 of the machine and support an auxiliary weft beam 17 from which weft threads 1 are taken off and supplied through a stationary comb 18 to the weaving plane of the machine.

The produced fabric 19, supported on a stationary flat support 20 with a leading edge 21, is transported by a roller 22 and by a pressure roller 23 cooperating therewith, and finally wound up on the cloth beam 24.

The uniform take-off of the weft thread 1 and warp thread 3 from the beams 12 and 17, respectively, is controlled by well known devices either by a brake, or positively by well known let off motions.

The machine is driven by an electric motor 25 by means of a V-belt 26 and a pulley 27 keyed to the shaft 21 outside of the respective lateral frame wall 11. The shaft 28 carries two shed forming cams 29, 30 cooperating with cam followers 31 which are pivotally connected with heddle frame lifting levers 32, 33, respectively, levers 32, 33 being connected by connecting members 34 to the heddle frames 14 and 15.

A cam shaft 37 imparts by means of a connecting rod 38, a reciprocating swinging movement to a sley 39 which is provided with a reed 40 and pivotally supported on stationary pivots 41 which are secured to the lateral frame walls 11. Cam shaft 37 is driven from shaft 28 by means of gears 35, 36 meshing at a transmission ratio of 2 : 1.

As shown in FIGS. 2, 3 and 4, a crossbar 42 is positioned between the lateral frame walls 11 in the space below the warp threads 3, and between the heddle frames 14, 15 and the stationary flat support 20. A row of lapping guides 43 is supported on crossbar 42, each lapping guide 43 being mounted for oscillating angular movement about a vertical axis 44, as best seen in FIG.

4. Each lapping guide 43 has a stem portion 45 extending in axial direction, and an intermediate portion with a lapping arm 46 which is provided with a thread guiding eyelet 47 through which the weft thread 1 passes. The lapping guides 43 are preferably manufactured by stamping of a steel sheet blank whose thickness may be between 0.3 and 0.8 mm. The edges of the lapping arm 46 converge at an angle substantially corresponding to the angle formed by the two groups of warp threads 3 when a warp shed is open.

All lapping guides 43 are coupled to simultaneously oscillate in the same direction about the vertical axis 44. The lapping guide stem 45 has a lower cylindrical journal portion 45' mounted in a corresponding bearing bore in crossbar 42, and having a projection or tooth 48 meshing with a rack bar 49 which is mounted for reciprocating movement in the crossbar 42, as best seen in FIGS. 4 and 5. The reciprocating movement of the rack 49 in the direction of the double arrow 50, 50', see FIG. 3, is derived from a cam 51 carried by the cam shaft 37 which is driven from shaft 28 by gear wheel gears 35, 36. Cam 51 is formed as a cam groove receiving a follower 52 secured to an end portion of rack bar 49, as shown in FIG. 2.

When the warp shed is changed while the sley 39 is in its rear dead center position, the lapping guides 43 are simultaneously moved from their intermediate initial position I shown in FIG. 9 to the extreme right-hand lapping position II, shown in FIG. 6, and back again to the intermediate initial position I, shown in FIG. 7. Upon the next warp shed change, the lapping guides 43 move from the intermediate initial position of FIG. 7 to the extreme left hand lapping position III shown in FIG. 8 and then back again to the intermediate initial position I shown in FIG. 9.

Between the dents 53 of reed 40 through which the warp threads 3 pass, as shown in FIG. 3, wider spaces 54 are provided at regular intervals in order to permit a smooth passage of the lapping guides 43 therethrough during the oscillating movement of sley 39. Irrespective of the width of the spaces between dents 53, reed 40 is threaded, for instance, by two warp threads in each space between dents 53. If a loosely constructed fabric is made, it is possible to use a reed having a wide uniform spacing between the dents.

In the intermediate initial position of the lapping guides 43, the eyelets 47 point toward the apex of the warp shed which is being formed so that the dents of the reed 40 can freely pass on both sides of the lapping guides during reciprocating movement of reed 40.

Between the lapping guides 43 there may pass warp threads 3, and weft threads 1 drawn through the eyelets 47 of the lapping guides 43. The height of the lapping guides 43 is selected so that the top of stem 45 may overlap the warp threads 3 of the upper warp shed plane in the open shed position, as shown in FIGS. 2, 3 and 4, in order to assure the desirable separation between weft threads 1 and warp threads 3 during the weaving operation.

The stem 45 of each lapping guide 43 is connected with the lapping arm 46 by curved concave edge portions 55 and 55', best shown in FIG. 10. The lapping guides 43 may be modified by providing the stem, which may have a circular cross section, with a perpendicular arm terminating in an eyelet 47. The triangular shape of the lapping arm 46, as illustrated, is preferable

inasmuch as it prevents a snarling of the warp ends during a warp shed change.

During oscillation of the lapping guides 43 about axis 44, the weft thread guiding eyelets 47 move along circular paths which intersect one another and have the same radius. The circular paths of the eyelets 47 are located in the plane 3' formed by the warps 3 in the closed shed position, as shown in FIGS. 2 and 4.

A knitting latch needle 56, which will be referred to hereinafter as a knitting needle, is located opposite each lapping guide 43. The longitudinal axis of each knitting needle 56 points in the initial position I of the lapping guides 43, toward the eyelet 47 of the respective lapping guide 43, as shown in FIGS. 7 and 9. The knitting needles 56 are secured in a movable holder 57 provided with a sleeve 58 which surrounds a cam 59 secured to a shaft 60, as best seen in FIG. 4, but also shown in FIGS. 2 and 3. Shaft 60 is mounted for rotation in bearings, not shown, in the lateral frame walls 11, and carries a sprocket 61 connected by an endless chain 62 with another sprocket 63 keyed to the cam shaft 37, as shown in FIG. 2. The transmission ratio between shafts 37 and 60 is 1 : 1.

Hooks 64 of the knitting latch needles 56 move along an endless curved path 65 in the direction of the arrow 66 in FIG. 4 from the foremost position to a retracted position and back again during each revolution of cam shaft 37. The endless path 65 is shown in FIG. 4 as a phantom line. The direction of rotation of cam 59 is indicated by an arrow 67, and the latch of the knitting latch needle 56 is designated by reference numeral 68. FIGS. 6 to 9 also show the fell 69 of the fabric 19.

The movements of the lapping guides 43 are synchronized with the movements of the knitting needles 56 and of the sley 39. As the sley 39 moves to its rear dead center position, the knitting needles 56 are simultaneously retracted from the foremost position to the rearmost position, and the sequence of movements is selected so that the needles 56 reach the rearmost position after sley 39 reaches its rear dead center position. Immediately after the lapping guides 43 have angularly moved from the intermediate initial position shown in FIGS. 7 and 9 to the extreme lapping end position II and III shown in FIGS. 6 and 8, respectively, the knitting needles 56 reach the rearmost position. These mutually interdependent movements are selected to reliably place the weft thread 1 into the hooks 64 of the knitting needles 56. During the return movement of knitting needles 56 to the foremost position, the hooks 64 will slightly lift the weft thread 1 in the region between the fell 69 of the fabric 19 and the thread guiding eyelet 47 of the respective lapping guides 43.

In the embodiment of the invention illustrated in the drawing, a plain weave harness with two heddle frames 14 and 15 is used, although it is possible to provide the machine with a multiple heddle frame harness controlled by a shed forming cam mechanism adapted to produce atlas, twill and like weaving patterns. The machine may also be provided with a dobby or Jacquard motion.

The weaving speed is not limited by the width of the reed 40 but depends on the type of shed forming mechanism so that the maximum speed may be obtained, for instance, by using a plain weave shed forming mechanism with a cam driven harness.

The sley 39 may be driven in the conventional manner, i.e., from the cam shaft 37, as described, or in any

other way bringing about the necessary dwell of the sley in the rear dead center position.

In order to assure the desired operation of the machine according to the invention, it is necessary that sley 39 dwells after completion of a revolution of cam shaft 37, in its rear dead center position for a time period corresponding to at least 45° of the next following revolution of cam shaft 37. The shorter the dwell of sley 39 there is in the rear dead center position, the higher must be the oscillation frequency of the lapping guides 43b during displacement of the lapping guides 43 from the intermediate initial position I to one of the extreme lapping positions II and III and back again, respectively. Therefore, it is advisable that the dwelling period of the sley in the rear dead center position is longer, for example 60° to 120° of the revolution of cam shaft 37. In order to obtain the dwell of sley 39 for a period of time corresponding to the angle of about 120° of a cam shaft revolution, it is possible to make use of conventional sley driving mechanisms comprising connecting rods and cam systems, or multiple joint links.

The machine described with reference to FIGS. 1 to 10 operates as follows:

During operation, the levers 32, 33 move in opposite direction upward and downward so that during each revolution of the drive shaft 28, the heddle frames 14, 15 will form sheds of warp 3 to make a plain weave, as best shown in FIGS. 2 and 4.

During each revolution of cam shaft 37, cam 51, see FIG. 2, shifts the rack bar 49 at intervals forward and rearward in the direction of the double arrow 50, 50', see FIG. 3. When the sley 39 is moved from its front dead center position to its rear dead center position, the knitting needles 56 are simultaneously retracted in the direction of the arrow 66 from the foremost to the rearmost position, see FIGS. 3 and 4. As soon as sley 39 has reached its rear dead center position, it which it dwells for a certain time period, the rack 49 is displaced, for example in the direction of the arrow 50, so that the lapping guides 43 swing simultaneously in one angular direction so that the eyelets 47 with weft threads 1 therein, are displaced from the intermediate initial position I to the extreme lapping position 11, see FIG. 6 and 10.

After the lapping guides 43 have reached the end position II, the knitting needles 56 are retracted to the rearmost position while the open hooks 64 are located under taut weft threads 1 which, in the wale regions 6 are secured under the knitting needles 56 to the fabric being woven so that the weft threads 1 enter the hooks 64. In this manner, the first parallel legs of the connecting weft loops 4 of stitches 5 are formed of weft thread portions of weft thread 1 taken off the auxiliary beam 17. Still during the dwell of sley 39 in the rear dead center position, rack bar 49 is shifted back in the direction of arrow 50' so that the lapping guides 43 swing back to the intermediate initial position I to form the second legs of the stitch connecting loops 4, as shown in FIG. 7.

Simultaneously with the movement of sley 39 from the rear dead center position to a front beat-up position, the knitting needles 56 are returned back to the foremost position thereof, together with stitches 5 caught in the hooks 64, carrying at the same time the first legs of the stitch connecting loops 4 to the beat-up plane of the fabric 19. After the return of the lapping

guides 43 to the intermediate initial position I, the reed 40 beats the second legs of the connecting loops 4 of stitches 5 into the fell of the fabric 19 while the warp shed changes at the same time. In this manner, a new sectional weft 8 is provided. During the retraction of the knitting needles 56, the latches 68 of the knitting needles 56 are closed, by drawing the preceding stitches 5 over the new stitches 5 so that the wale 6 is formed. During the formation of the next warp shed, the above-described operation is repeated, with the exception that the lapping guides 43 are moved from the intermediate position I to the lapping end position III and back again, see FIGS. 8 and 9, whereby the next sectional weft 8 is formed, of which stitches 5 are oriented in opposite direction with regard to the preceding sectional weft 8.

Each knitting needle 56, except the marginal knitting needles 56', forms a warp knit thread structure in cooperation with the two lapping guides 43 disposed adjacent to, and on the right and left of the lapping guide 43 which, in its intermediate initial position I, is located directly opposite the respective knitting needle 56. For instance, in FIG. 9 the knitting needle 56" cooperates with the lapping guides 43', 43" which are located on opposite sides of the lapping guide 43 which is aligned with the knitting needle 56". As is apparent from FIG. 1, each knitting needle 56 interlaces all the stitches pointing toward the same gap between two adjacent stripes 2, to form the wales 6.

The marginal knitting needles 56' cooperate only with a single lapping guide 43 positioned on the right or left of the marginal knitting needle 56'.

As lapping guides 43 swing from the lapping end position III shown in FIG. 8 to the intermediate initial position I shown in FIG. 9, the weft thread 1 threaded into the left marginal lapping guide 43, is not engaged by the knitting needle 56, but is connected by the loop link 9, see FIG. 1, with the second following sectional weft 8 where it forms again a complete loop due to the movement of the lapping guides 43 from the intermediate initial position I shown in FIG. 9 to the lapping end position II shown in FIG. 6, and back again. The marginal stitches 5' overlap the marginal warp thread 3, see FIG. 1, and tie the loop links to the selvedge of the fabric 19.

In the same manner, as the lapping guides 43 are moved from the intermediate initial position I shown in FIG. 9 to the lapping end position II shown in FIG. 6, and back again, see FIG. 7, the opposite selvedge, not shown, of fabric 19 will be formed.

Since each of the marginal lapping guides 43 having a weft thread 1 in its eyelet, swings from its initial intermediate position I only to one of the two lapping end positions, for example lapping end position II, a lesser length of weft thread 1 is required so that this weft thread 1 has to be taken off a package on a separately braked reel.

The lapping guide mechanism and the knitting needles 56 cooperate in a well known manner to form either open or closed stitches 5 in the wale 6. The open stitches 5 of wale 6 are formed by laying the weft thread 1 into the hook 64 of the knitting needle 56 from above, as shown in FIG. 4.

In the event that cam 59 rotates opposite to the direction of the arrow 67, the weft thread 1 is laid into the hook 64 of the needle 56 from below so that the stitches 5 of the connecting wale 6 are closed.

The manner in which open and closed stitches are formed by a knitting mechanism is well known, and is described, for example in the U.S. Pat. No. 3,580,295.

Due to the mutual interlacing of stitches 5 to form wales 6, a striped pattern effect is produced in fabric 19. The spaces between the stripes 2 can be selected in accordance with the type of fabric to be made. For instance, for shirting, dense stripes will be preferred, while for woolen material for outerwear, broad stripes are more suitable.

The spacing of the wales 6 in fabric 19 can be chosen with regard to the amplitude, or the angle of oscillating movement of the lapping guides 43, which angle is to be smaller than 45°. The desired width of the spacing is obtained by adjusting the length of the arm 46 of the lapping guides 43 accordingly, for instance in the case of denser stripes, the lapping arm 46 must be made shorter than for wide stripes. It is obvious that any change in the length of the lapping arms 46 will require a corresponding spatial arrangement of the knitting mechanism. In the fabric shown in FIG. 1, the adjacent wales are separated from each other by four warp threads 3, whereas in the fabric 19 schematically illustrated in FIGS. 6 to 9, two warp threads 3 extend between two adjacent wales 6.

In practice, however, there is no limitation in the number of warp threads 3 interlaced within the longitudinal stripes 2 or 2'. The number is chosen under consideration of the final use of the fabric, in the same manner as for conventional woven fabrics having similar weaving patterns.

The warp threads 3 in the several longitudinal stripes may vary both in number and quality so that it is possible to produce fabrics with stripes of varying width, or fabrics with different warps in the individual stripes.

In the embodiment of the machine shown in FIG. 3, the lapping guides 43 are arranged in such a manner that the lapping arms 46 point with eyelets 47 toward the apex of the warp shed when the lapping guides are in the intermediate initial position I. As explained above, the reed 40 in its forward beat-up position is located beyond the lapping guides 43, whereas the reed 40 in the rear dead center position is penetrated by the lapping guides 43. Due to this arrangement of the lapping guides 43, and especially of the lapping arms 46, a relatively large opening of the warp shed is required which, to some degree, prevents a very high weaving speed.

In FIGS. 11 and 12, a weaving mechanism is schematically illustrated in which the arrangement of the lapping guides 43a makes possible the use of a warp shed forming a smaller acute angle than the warp shed shown in FIG. 3.

A mechanism for actuating the lapping guides 43a is mounted on a crossbar 42a secured by screws, not shown, to the stationary support 20a. Each of the lapping guides 43a is bent of a wire having a flat or circular cross-section, and includes a stem 45a with a projecting portion 48a, and with a lapping arm 46a projecting in the opposite direction. Lapping arm 46a merges into a vertical top end portion which is coaxial with stem 45a and with a bottom end portion of the respective lapping guide 43a so that each lapping guide can turn about the vertical axis 44a in a bore receiving its lower end portion in crossbar 42a.

The lapping arm 46a has the shape of an isosceles triangle whose apex is located in the plane of the warp

threads 3 in the closed shed position, and has at the extremity thereof a guiding eyelet 47a, best seen in FIGS. 13 and 14, receiving the weft thread 1. Eyelet 47a is not closed so that threading-in operations are facilitated. 5 The central portion of stem 45a is also located in the bearing bore of a plate 70 which is secured by screws, not shown, to the crossbar 42a. The projections 48a which are received in a recess 71 between crossbar 42a and plate 70, mesh with the teeth of a rack bar 49a 10 operable by the same cam mechanism as described with reference to the machine shown in FIGS. 2 to 5.

The axis 44a of the lapping guides 43a is substantially perpendicular to the warp plane 3' in which warp threads 3 are located in the closed shed position. The 15 thread guiding eyelets 47a point, in the intermediate initial position aligned with the warp threads 3, toward the heddle frames 14, 15. Knitting needles 56 located in holder 57 in the same manner as described with reference to FIG. 4, are reciprocated in the same manner as described with reference to FIG. 4, moving from a foremost position in the beat-up plane 69 to the rear-most position in the open warp shed, and back again.

Due to the arrangement of crossbar 42a, the reed 40a has an angular shape, and its two portions 72 and 73 intersect at an angle of about 100°. In the rear dead center position of reed 40a shown in full lines in FIG. 11, the reed 40a is situated beyond the eyelets and extremities of the lapping guides 43a, whereas in the beat-up position, shown in broken lines, the reed portion 73 passes between the lapping guide stems 45a so that its other effective portion 72 is located near the edge of support 20a in the region of the fell of the fabric 19.

For clarity's sake, the warp thread 3 and the reed 40a have been omitted in FIG. 12. During operation of the 35 machine, when the slay is in the rearmost position, the lapping guides 43a swing from the intermediate initial position parallel with the needles 56, to the lapping end position II, see FIG. 12, in which the weft threads 1 are laid into the hooks of the knitting needles 56 which at this moment are operative and located in the open warp shed. After the weft threads 1 have been laid, the lapping arms 46a are returned to the intermediate initial position, and the reed 40a beats up the just formed stitch connecting loops into the fell of the fabric so that another sectional weft 8' is made. During the rearward movement of the knitting needles 56, the wale 6 consisting of stitches 5 is formed, as described above. When the next warp shed is opened again, the lapping guides 43a swing to the opposite lapping end position, and the cycle is repeated.

The thread guiding eyelets 47a of the lapping guides 43a swing in the region of the maximum shed opening so that it is possible to use a shed with a reduced transverse maximum extension, as compared with the arrangement described with reference to FIG. 3.

Since in the closed shed position, the lapping guides 43a pass through the spaces between the individual warp threads 3, and in the open shed position, see FIG. 11, pass between the two planes in which the warps are located, a stable position of warp threads 3 in relation to the knitting mechanism is assured, as is absolutely necessary in view of the operations carried out by the knitting mechanism.

FIGS. 15 and 16 schematically illustrate a knitting machine comprising lapping guides 43b whose axis of oscillation 44b is perpendicular to the warp plane 3' in which the warp threads 3 are located when the warp

shed is closed. The axis 44b passes substantially through the beat-up plane 69, warp threads 3 and reed 40b being omitted in FIG. 16 for the sake of simplicity. In this modification, the crossbar 42b is secured to the bottom of the stationary support 20b whose leading edge 41b defines the beat-up plane 69. The lapping guides 43b may be made of a flattened wire formed with stem 45b merging at the upper end into the lapping arm 46b terminating in an eyelet 47b, which advantageously has the shape of a hook, and at the bottom end into a projection 48b formed of a doubly bent wire portion which is generally U-shaped. The projections 48b mesh with a rack bar 49b which is controlled by actuating mechanism as described with reference to FIGS. 2 to 5. The stem portions 45b of lapping guides 43b are mounted in grooves, not shown, in the front wall of the stationary support 20b and held in position by a plate portion 74 which is attached by screws, not shown, to the stationary support 20b to form a guideway for the rack bar 49b.

The knitting needles 56 are arranged in the same manner as described with reference to FIGS. 11 and 12. The reed 40b is mounted on the sley 39b, and is straight since the axis 44b of oscillation of the lapping guides 43b is located in the beat-up plane 69.

In the intermediate initial position, in which a perpendicular projection of lapping arms 46b onto the warp plane 3' of the warp threads 3 in the closed shed position, is parallel with the warp threads 3, the lapping arms 46b point with the respective eyelets 47b toward the heddle frames 14, 15 while the reed 40b is in the beat-up position in which the lapping arms 46b have passed through the spaces of reed 40b. In the lapping position of the lapping arms 46b, the reed 40b is located in its rear dead-center position, beyond the lapping guides 43b as shown in solid lines in FIG. 15.

As reed 40b is moved from the beat-up position to the rear dead center position, the knitting needles 56 enter the opening warp shed. Before the knitting needles 56 have reached the operative position inside the opened warp shed, the lapping arms 46b swing into one of the lapping end positions, as shown in FIG. 16. The eyelets 47b, which are threaded with the weft threads 1, are located at this moment in such a position that during the swinging movement of the lapping guides 43b, the weft threads 1, extending from the eyelets 47b to the beat-up plane, are laid into the hooks of the knitting needles 56. The backward movement of the knitting needles 56 and of the lapping guides 43b is timed in such a way that after the weft threads 1 have been caught by the knitting needles 56, the knitting needles 56 are returned to their initial position before the lapping arms 46b again arrive in the intermediate initial position extending in warp direction.

After the knitting needles 56 and the lapping guides 43b have returned to their respective initial positions extending in warp direction, the reed 40b beats up the just formed stitch connecting loops 4 into the fell of the fabric 19 while the warp shed simultaneously changes, whereupon the operations of the mechanism will be repeated, except that the lapping arms 46b swing now in the opposite lapping direction, as explained with reference to FIGS. 6 to 9.

In the closed position of the warp shed, the lapping guides 43b pass through spaces between all warp threads, while in the open shed position, the lapping guides 43b pass only between the warp threads 3 of the

lower groups of warp threads of the warp, as shown in FIG. 15.

In contrast to the arrangement shown in FIG. 11, the lapping guides 43b are bent substantially 90° between stem 45b and lapping arm 46b, so that the bent portion separates the warp threads 3 in the beat-up plane in the closed shed positions, and thus ensures that each of the knitting needles 56 will enter the warp shed always through the same space formed between specific warp threads 3.

While in the embodiments of the knitting mechanism illustrated in FIGS. 4, 11 and 15, the axes 44, 44a, 44b about which the lapping guide oscillate, extend substantially perpendicularly to the warp plane 3' where the warp threads 3 are located in the closed shed position, while the circular paths along which the weft thread guiding eyelets 47, 47a, 47b, are substantially located in the closed shed position within the same plane. For laying the weft threads 1 into the hooks of the knitting needles 56 by means of lapping guides 43, 43a, 43b, it is necessary that the respective hooks 64 of the knitting needles 56 may move along a curved endless path 65 within the open shed, as shown in FIG. 4.

However, it is preferable that a knitting needle 56 is reciprocated along a straight path, or along a slightly curved path while the actual insertion of the weft thread 1 into the hook 64 of the knitting needle 56 is carried out by a lapping guide.

FIG. 17 illustrates a knitting mechanism in which the knitting needles 56 perform a reciprocating linear movement indicated by the double arrows 75, 76, and lapping guides 43c oscillate about an axis 44c which is slanted to the warp plane 3' of the warp thread 3 in the closed shed position.

Lapping guides 43 have a shape similar to the lapping guides described with reference to FIG. 4, and have the stems 45c pivotally supported in bearings 77 provided in the stationary crossbar 42c to which they are secured by a closure plate 78. Projections 48c of the lapping guides 43c mesh with a rack bar 49c which is reciprocated as described with reference to FIG. 2 while being guided in a guideway of the stationary crossbar 42c.

The axis 44c of each lapping guide 43c defines an angle between 25° and 45°, preferably 30°, with the plane 3' formed by the warp threads 3 in the closed shed position. The lower edge 80 of the lapping arm 46c extends substantially parallel to the lower group of warp threads of the warp in the open shed position. Lapping arm 46c, which in its intermediate initial position points toward the beat-up plane 69, ends in an eyelet 47c into which weft thread 1 is threaded. Warp threads 3 are drawn alternately through heddles of heddle frames 14, 15; 14', 15'.

Knitting needles 56 are slidably supported in channels, not shown, in a stationary guiding bed 81, and have shaft end portions fixed in a needle bed, not shown, which is reciprocated in a linear motion in the direction of the double arrow 75, 76. For example, needles 56 may be reciprocated by a connecting rod operated by a cam mechanism disposed below the fabric 19.

A support 20c is located below the guiding bed 81 which has a leading edge 21c which forms with the lower edge of guiding bed 81, a gap for the passage of fabric 19.

Reed 40c is mounted on sley 39c, only partially shown, and has an angular shape with two portions 82 and 83 forming an angle of substantially 110°. In the

rear dead center position, portion 82 of reed 40c is parallel with the axis of oscillation 44c of the lapping guides 43c, while the stems 45c of lapping guides 43c pass through the spaces of the reed portion 83. In the beat-up front dead center position shown in phantom lines, the reed 40c is located beyond the lapping guides 43c.

When the lapping arm 46c swings from its intermediate initial position I, shown in FIG. 18, to one of the two lapping end positions II and III, respectively, the respective eyelet 47c moves along a circular arc 84, and during such movement, the eyelet 47c is either aligned with, or situated above the level of the movement of the knitting needles 56 when the eyelet 47c is in the intermediate initial position I. However, in the two lapping end positions II and III, the eyelet 47c is always located below this level. As shown in FIG. 17, the lapping guide 43c is in the lapping end position II in which eyelet 47c is located below the plane of movement of the knitting needles 56.

As the reed 40c is displaced from its front dead center position located in the beat-up plane to its rear dead center position, the knitting needles 56 enter the opening warp shed. Before the knitting needles 56 have reached the operative position inside the open warp shed, the lapping arms 46c swing into one of the lapping end positions II or III, and lay the weft thread 1, which extends from the fell 69 of fabric 19 to the guiding eyelet 47c, into the hooks of the knitting needles 56, as shown in FIG. 17. After the weft threads 1 have been laid into the hooks of the needles 56, the needles are retracted to the initial position before the lapping guides 43c return to the initial position.

The lapping guides 43c separate the warp threads 3 from one another in the intermediate initial position, as well as in the lapping end positions.

An important feature of the embodiment illustrated in FIG. 17 is that the eyelets 47c are located in the lapping end positions below the level of movement of the knitting needles 56, while they are aligned or located above this level when placed in the intermediate initial position I.

The knitting mechanisms described above, have in common that the oscillation axes 44, 44a, 44b, and 44c of the lapping guides 43, 43a, 43b and 43c, respectively, have a stable position defined by bearings in stationary crossbars 42, 42a, 42b, and 42c.

The weaving mechanism schematically illustrated in FIGS. 19 to 21, has a crossbar 42d which forms part of the beam of sley 39d, and moves with the same. Crossbar 42d supports lapping guides 43d for angular movement by means of stems 45d supported in bearing openings 85 in the upper portion of crossbar 42d for pivotal movement. Lapping arm 46d projects upward from stem 45d, and has at its free end, the eyelet 47d into which weft thread 1 is threaded. At the opposite end portion of stem 45d, a projection 48d is provided, meshing with a rack bar 49d which is reciprocated by a cam 86 supported on crossbar 42d for rotation. Cam 86 can be driven by any conventional transmission, for example by bevel gearing from the shed forming shaft which operates the heddle frames 14, 15. Rack bar 49d reciprocates in the direction of the double arrow 50, 50', as described with reference to FIG. 3.

When sley 39d is in the rear dead center position, the axes 44d of the lapping guides 43d are located substantially parallel with the warp plane 3' of warp threads 3

in closed shed position, or they can extend substantially parallel with warp threads 3 located in the lower warp.

In the embodiment of the machine illustrated in FIGS. 19 to 22, a conventional reed is omitted. The function of the reed is carried out by lapping arms 46d which, while the sley 39d is in its foremost position, beat up the just formed stitch connecting loops into the fell of fabric 19, within the beat-up plane 69.

A comb 87 is provided on crossbar 42d, and includes pins or prongs 88 which are parallel with lapping arms 46d when the same are in the intermediate initial position extending in warp direction.

Lapping arms 46d and pins 88 are aligned, respectively, in warp direction. Each pin 88 is provided with a slot 89 extending from its top end to about half of its effective length, and being threaded with the weft thread 1. The length of the slotted pins or prongs 88 is selected so that the free end portions of the prongs 88 extend between the warp threads of the upper group of warp threads of the warp in the rear dead center position of sley 39d, as shown in FIG. 21.

The comb assures, on the one hand, a steady position of the warp threads 3 passing therethrough, and on the other hand, it guides weft threads 1 directly to the region where they are engaged, while separating the weft threads from the warp threads 3. The pins 88 need not be necessarily provided with slots 89, and it is possible to pass each weft thread 1 between two adjacent pins 88 of comb 87.

In order to save space, pins 88 are preferably disposed parallel with the plane of movement of the lapping arms 46d.

As shown in FIGS. 21 and 22, each lapping arm 46d defines substantially a right angle with the axis 44d and with the respective stem portion which is supported in bearings of support 42d. It is also possible to modify the position of the lapping arms so that the lapping arms 46d extend at an obtuse or acute angle to the supported stem portions.

The oscillation axis 44d of each lapping guide 43d can be either parallel with the lower warp shed plane or with the upper warp shed plane. In any event, it is necessary to dispose comb 87 on the crossbar 42 accordingly, and to choose a corresponding plane of movement for the knitting needles 56.

The knitting needles 56 are fixed in a holder 57 which is operated from a cam mechanism, not shown, to perform a linear reciprocating movement in the direction of the double arrow 75, 76. In order to assure a reliable engagement of the weft threads by the hooks of the knitting needles 56, the knitting needles 56 may be moved along a slightly curved path.

Irrespective of whether a conventional reed is used, or whether the beating element is formed by the lapping guides 43d, the function of the beating element is to beat up the leg portions of stitch connecting loops, one end of which is engaged by the hook of the adjacent knitting needle 56, the other end is engaged by the eyelet of the respective lapping guide. For this reasons, and furthermore, since the force required for beating up the weft thread 1 and also the width of the longitudinal stripe 2 are relatively small, one or two reed dents are, as a rule, sufficient for beating up one of the stitch connecting loops within one longitudinal stripe 2.

In the embodiment illustrated in FIGS. 19 to 22, each lapping arm 46d assumes the beating up function of the respective reed dent within each longitudinal stripe 2.

As sley 39d moves from the front beat-up position to its rear dead center position, the lapping arms 46d of the lapping guides 43d swing into one lapping end position so as to reach the end position when the sley is in its rear dead center position. Simultaneously with the movement of sley 39d, the knitting needles 56 enter the warp shed from the beat up plane 69, and due to the movement of the lapping arms 46d, the weft threads are laid into the hooks of the needles. After the weft threads have been caught by the hooks of the knitting needles 56, the needles 56 return to their starting position, while the lapping guides 43d, together with sley 39d, move into the beat-up position in which the lapping arms 46d beat up the stitch connecting loops produced in the beat-up plane 69 between two adjacent stitch wales, whereupon the stitch loops 4, 5 will then be tied to the fell of the fabric 19 by changing of the warp shed.

The circular arcs along which the eyelets 47d of the lapping guides 43d swing while the sley 39 is in its rear dead center position, are substantially perpendicular to the imaginary warp plane formed by warp threads 3 in the closed shed position. The thread guiding eyelets 47d are located above the hooks of the knitting needles 56 when the lapping guides are in the intermediate initial position, whereas in the two lapping end positions of lapping guides 43d, respectively, the eyelets 47d are located below the level of the knitting needles 56 so that the weft threads 1 are laid into the hooks of the knitting needles 56 due to the movement of the lapping guides 43d. However, as described above, it is possible to arrange the knitting needles 56 to move within the open warp shed along a curved path, whereby a more reliable lapping, particularly at relatively high speeds, is ensured.

The above-described modifications of a mechanism according to the invention, employ lapping guides 43d which move alternately to two lapping end positions. In another embodiment of the invention, a mechanism is used in which the lapping guides swing at each warp shed change to the same lapping end position. In such an arrangement the cam 51, shown in FIG. 2, must be designed to make rack bar 49 reciprocate out of a starting position only in one direction.

In the above-described embodiments of the invention, the lapping arms 46 of the lapping guides 43 always point toward the hooks of the respective knitting needles 56, when in the intermediate initial position I, as shown in FIG. 7. The axes of oscillation 44 of each lapping guide 43, and also the knitting needle 56, are always located in a space between the two marginal warp threads 3 of two adjacent longitudinal stripes 2. In view of this arrangement, the fabric structure illustrated in FIG. 1 is obtained if alternate lapping in both directions out of the intermediate initial position I is carried out, whereas in the case of one sided lapping, a fabric structure as shown in FIG. 23 is obtained.

In order to produce the fabric shown in FIG. 23, the mechanism shown in FIGS. 24 and 25 is used in which the lapping guides 43 swing from the intermediate initial position I to the lapping end position II and then back again to the initial position I. When lapping guides 43 are in the lapping end position II, they lay the weft thread 1 into the hooks of the knitting needles 56.

The fabric as shown in FIG. 23 has been disclosed in the U.S. Pat. No. 3,580,295.

In another embodiment of the mechanism of the invention, shown in FIGS. 26 and 27, the lapping guides 43 and the knitting needles 56 are arranged so that each lapping guide is always located in the middle between two adjacent knitting needles 56. When alternate lapping in both directions out of the intermediate initial position of the lapping guides 43 is carried out as shown in FIGS. 26 and 27, the fabric structure illustrated in FIG. 28 is obtained. If one sided lapping is used, as shown in FIGS. 30 and 31 in which the lapping guides 43 only move in one direction out of the intermediate initial position I, the fabric shown in FIG. 29 is obtained in which the weft thread sections are laid more densely in the spaces 90 between two adjacent warp threads 3.

FIG. 32 schematically shows a machine having lapping guides 43e pivotally mounted in the crossbar 42e which forms a portion of sley 39e. In the position of warps 3 in which the warp shed is closed, the oscillation axis 44e of each lapping guide 43e is perpendicular to the warp plane 3' when the sley 39e is in the rear dead center position. The lapping arms 46e in the intermediate initial position of the lapping guides 43e are pointed toward the beat-up plane 69.

An embodiment of the lapping guide 43e is illustrated in FIG. 33. Lapping guide 43e is made of one flat piece of a band or round wire, and has a top end portion axially aligned with the journal end portion 45e. The top end portion merges by a curved portion 91 into the lapping arm 46e which has two portions 92 and 93 which converge toward a rounded apex 94 provided with a weft thread guiding eyelet 47e. The lower portion 93 merges by two curved portions 95 and 96 into a U-shaped projecting portion 48e which is connected by the curved portion 97 with a journaled portion 45e which is mounted in a bearing bore of the crossbar 42e. Eyelet 47e is a hole at the apex 94 of the lapping arm 46e. Portions 92, 93, 94 of the lapping arm 46e form a substantially triangular space 98.

A modified lapping guide 43f is shown in FIG. 34, and is stamped of sheet metal. The projecting portion 48f which cooperates with the rack bar 49, as described above, is made as a flat rectangular sheet portion. The lapping guides are mounted on a sley 39e which reciprocates between a front beat-up position and a rear dead center position in which the sley dwells during the lapping operation.

Lapping guides 43e cooperate with the knitting needles 56 whose hooks 64 follow an endless closed curved path from the foremost to the rearmost positions and back again during a single revolution of the machine cam shaft, as described with reference to FIG. 4.

The fabric 19 is taken off over a support plate 20, as shown in FIG. 32. The warp threads are held by the heddles of the heddle frames 14, 15, while the weft threads 1 pass through the eyelets 47e of the lapping guides 43e.

At the same time as sley 39e moves from the foremost dead center position to the rearmost dead center position, one knitting needle is displaced from the foremost to the rearmost position thereof. As soon as sley 39e has reached the rear dead center position in which it dwells, the lapping guides 43e swing into one of the two lapping end positions, for example lapping end position III shown in FIG. 35, while the eyelets 47e form parallel sections of weft threads 1 caught in the wale regions 6. After reaching the extreme lapping position

III, the knitting needles 56 enter from below into the rear position and pass with their open hooks 64 under the tensioned sections of the weft threads 1 held by the lapping guides 43e. While the sley 39e is still dwelling in its rear dead center position, the lapping guides 43e are returned back to the intermediate initial position extending in warp direction, not shown in FIG. 35. Simultaneously with the movement of sley 39e from the rear dead center position to the front beat-up position, the knitting needles 56 together with the weft thread 10 stitches caught in the hooks 64, are displaced and bring the first legs of the stitch connecting loops 4 into the fell of the fabric and the beat-up plane.

After the lapping arms 46e have returned to the intermediate initial position, the apices 94 of the lapping arms 46e, performing the function of the reed, beat up 15 the second legs of the connecting loops into the fell of the fabric 19, while the shed simultaneously changes. During the return movement of knitting needles 56, hooks 64 are closed by the latches or tongues 68, due 20 to the action of the old stitches which are drawn over the new stitches to form a wale.

During the time when the next warp shed is opened, the above-described operation is repeated, except that the lapping guides 43e are displaced to opposite lapping end positions II, and back again. 25

FIG. 32 shows the mechanism with lapping guides 43e in a lapping position, sley 39e being in the rear dead center position, while in FIG. 36, sley 39e is illustrated in the beat-up front position. 30

As is apparent from FIGS. 32 and 35, weft threads 1 are not obstructed in the lapping end position II of the lapping guides 43 by the lapping guides, since the weft threads 1 are located in the space 98 between the portions 92 and 93 of the lapping arm 46e.

The arrangement of lapping guides 43e, as well as the entire mechanism employing the lapping guides 43e, as shown in FIGS. 32 to 36, is therefore preferable to the mechanism in which the lapping arms 46 of the lapping guides 43 are triangular flat plates, as shown in FIG. 4. In the arrangement of FIG. 4, the weft threads 1 are bent over an edge of the lapping guide 43 so that the path of weft threads 1 is longer in one lapping end position than in the other lapping end position displaced toward the side where the supply reel of the weft thread 1 is located.

In order to obtain a high quality fabric, it is necessary that the knitting needles 56 enter an opening warp shed always in the gap between two adjacent longitudinal stripes 2 of the fabric, as shown in FIG. 1. If the knitting needles 56 enter the opening warp shed simultaneously with the movement of the reed from its beat-up position to the rear dead center position, or even later, some marginal warp threads may pass over from one longitudinal stripe 2 into another so that the respective marginal warp thread either does not bind with the weft thread, or impairs the weave in another way.

Therefore, it is advantageous, particularly with machines operating with conventional reeds, to exactly adjust the motion of the reed from its front dead center position to the motion of the knitting needles from the starting position so that the needles enter the opening warp shed before the reed has started to move out of its beat-up position.

FIG. 37 shows an operative condition in which the knitting needles 56 enter the opening shed before the reed 40 moves out of its beat-up front position. The

corresponding phase shift of the knitting needles 56 relative to the motion of sley 39 can be accomplished by adjusting the eccentric cam 59 accordingly on shaft 60.

In order to prevent irregularities in the formation of the connecting stitch wale 6 of the stitches 5, it is advantageous to provide in the beat-up plane between the fabric and the knitting needles, a device for knocking over stitches from the knitting needles.

For the sake of clarity, none of the above-described embodiments of the invention has been shown with a device for knocking over the stitches during the return movement of the needles, but the knocking-over device is a feature of the invention in combination with the disclosed knitting mechanism.

In a preferred embodiment, the knock-over operation is carried out by the edge of a steel strip disposed above the fabric 19 so that its operative edge is located above the beat-up plane, while the stroke of the knitting needles is adjusted so that in the retracted position of the needles, the tip of the hook of the needle is aligned with the edge of the knock-over strip.

A device for knocking over the stitches off the knitting needles is illustrated, by way of example, in FIG. 37 embodied as a thin steel blade 100 having an edge disposed closely above the beat-up plane of fabric 19, in the region between fabric 19 and the knitting needles 56. The blade 100 is fixedly secured to the side walls of the machine and extends across the warps.

In the apparatus described above with reference to FIG. 17, the knock-over of the stitches from the knitting needles 56 is effected by the leading edge of the stationary bed 81 in which the knitting needles 56 are mounted for sliding movement.

The operation of the knitting needles 56 has been described above. The weft threads 1 presented by the lapping arm 46 is engaged by the hook of a knitting needle 56 which during its rearward movement to the rear dead center position, will draw the end bight or head 40 of the caught loop through the stitch built of the end bight or head of the preceding weft thread, on the edge of the knock-over blade 100.

It will be understood that each of the elements described above, or two or more together, may also find 45 a useful application in other types of apparatus for partly weaving and partly knitting a fabric differing from the types described above.

While the invention has been illustrated and described as embodied in a weaving machine provided with lapping guides having arms with eyelets and being oscillated together along circular paths within each open shed, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims.

We claim:

1. In a machine for making a partly woven and partly knitted fabric, including shed forming means for moving the warp threads of a warp successively between an open shed position, and a closed shed position located in a warp plane, in combination, a knitting mechanism comprising a set of knitting needles arranged in a row across said warp; operating means for moving said knitting needles between forward and rearward positions; supply means for a set of weft threads; a cross bar extending across said warp outside of said sheds; a set of lapping guides mounted in a row on said cross bar for angular movement about parallel axes, said lapping guides penetrating said warp, and having projecting guide arms angularly movable in the open shed and having free ends with eyelets for said weft threads, said lapping guides having initial positions in which planes therethrough perpendicular to said warp plane intersect in said closed shed position said warp plane along lines parallel to the warp threads of said warp; and drive means for oscillating said lapping guides in synchronism with the movements of said knitting needles and with the changing of the sheds about said axes in an open shed between said initial position and at least one lapping end position while said eyelets move in the open shed along overlapping circular arcs for forming connecting weft loops of the weft threads, while laying the weft threads into said knitting needles in said rear position so that said knitting needles form knitted wales between fabric sections woven of said warp threads and said connecting weft loops, said lapping guides being returned to said initial position for passing between the warp threads when the shed is changed.

2. A knitting mechanism as claimed in claim 1, wherein said drive means oscillate said lapping guides to opposite lapping end positions while said shed forming means form two successive open sheds.

3. A knitting mechanism as claimed in claim 1, wherein said drive means include means located in said cross bar for angularly displacing said lapping guides with said lapping arms.

4. A knitting mechanism as claimed in claim 1, wherein each lapping guide has an axially extending stem forming a journal mounted in said cross bar, wherein said guide arm radially projects from said stem, wherein each lapping guide arm has a radial projection; and wherein said drive means include a rack bar mounted in said cross bar and engaged by said radial projections, and means for reciprocating said rack bar so that said lapping guides are angularly oscillated.

5. A knitting mechanism as claimed in claim 1, wherein said projecting guide arm of each lapping guide is formed by two slanted portions merging into a connecting apex portion having said eyelet so that a weft thread passing through said eyelet can pass between said slanted portions in said lapping end position.

6. A knitting mechanism as claimed in claim 1, wherein said cross bar is stationarily supported underneath open and closed sheds of said warps in the region between said shed forming means and the fell of the fabric.

7. A knitting mechanism as claimed in claim 1, comprising a stationary flat support for guiding the fabric and having a transverse edge extending across the fabric defining a beat up plane where the fell of the fabric is located; and wherein said cross bar is stationarily located under said support and secured to said support.

8. A knitting mechanism as claimed in claim 1, wherein said machine includes a reciprocating sley; and wherein said cross bar is mounted on said sley for movement with said lapping guides between a rear position and a front position.

9. A knitting mechanism as claimed in claim 1, wherein said parallel axes of said lapping guides are substantially perpendicular to said warp plane in the closed shed position.

10. A knitting mechanism as claimed in claim 1, wherein said parallel axes of said lapping guides are slanted to said warp plane in the closed shed position.

11. A knitting mechanism as claimed in claim 1, wherein said machine includes an angularly reciprocating sley having a rear position and a front position; wherein said cross bar is fixedly mounted on said sley; and wherein said parallel axes of said lapping guides are substantially parallel with said warp plane in the closed shed position when said sley is in said rear position.

12. A knitting mechanism as claimed in claim 1, wherein said machine includes an angularly reciprocating sley having a rear position and a front position; wherein said cross bar is fixedly mounted on said sley; and wherein said parallel axes of said lapping guides are substantially perpendicular to said warp plane in the closed shed position when said sley is in said rear position.

13. A knitting mechanism as claimed in claim 1, wherein said cross bar is stationarily supported by said machine; and wherein said circular arcs along which said eyelets move are substantially parallel with said warp plane in the closed shed position.

14. A knitting mechanism as claimed in claim 1, wherein said cross bar is stationarily supported in said machine; and wherein said circular arcs along which said eyelets move are substantially concurrent to said warp plane in the closed shed position.

15. A knitting mechanism as claimed in claim 1, wherein said machine includes a reciprocating sley; wherein said cross bar is mounted on said sley for movement therewith between a rear position and a front position; and wherein said circular arcs along which said eyelets move are in the rear position of said sley substantially perpendicular to said warp plane in the closed shed position.

16. A knitting mechanism as claimed in claim 1, wherein said machine includes a reciprocating sley; wherein said cross bar is mounted on said sley for movement therewith between a rear position and a front position; and wherein said circular arcs along which said eyelets move are in the rear position of said sley substantially parallel to said warp plane in the closed shed position.

17. A knitting mechanism as claimed in claim 1, wherein said machine includes a sley with a reed movable between a rear position and a beat up position located in a beat up plane at the fell of the fabric; and wherein said free ends of said projecting guide arms and said eyelets therein point toward said beat up plane in said initial position of said lapping guides.

18. A knitting mechanism as claimed in claim 1, wherein said machine includes a sley with a reed movable between a rear position and a beat up position located in a beat up plane at the fell of the fabric; and wherein said free ends of said projecting guide arms and said eyelets therein point toward said shed forming means in said initial position of said lapping guides.

19. A knitting mechanism as claimed in claim 1, wherein said machine includes a reed movable between a rear position and a beat up position and including dents for the passage of warp threads; and wherein said lapping guides pass through dent spaces of said reed in said rear position and are spaced from said reed in said beat up position of said reed.

20. A knitting mechanism as claimed in claim 1, wherein said cross bar is stationarily supported on said machine; wherein said machine includes a reed movable between a rear position and a beat up position, and a sley supporting said reed and being movable between a rear position and a front position; and wherein said lapping guides pass through dent spaces in said reed in said beat up position of said reed, and are spaced from said reed in said rear position of said sley.

21. A knitting mechanism as claimed in claim 1, wherein said machine includes a sley movable between a front position and a rear position; wherein said cross bar with said lapping guides is mounted on said sley for movement with said sley; and wherein said lapping guides in said initial position beat said connecting weft loops in said front position of said sley into the fell of said fabric.

22. A knitting mechanism as claimed in claim 1, wherein said machine includes a sley movable between a front position and a rear position; wherein said cross bar with said lapping guides is fixedly secured to said sley for movement with said sley; and comprising a comb mounted on said sley for movement therewith and having prongs forming gaps for receiving warp threads of said warp for separating said warp threads.

23. A knitting mechanism as claimed in claim 1, wherein said guide arms of said lapping guides in said

initial position register with said knitting needles, respectively.

24. A knitting mechanism as claimed in claim 1, wherein said guide arms of said lapping guides in said initial position are staggered relative to said knitting needles, respectively.

25. A knitting mechanism as claimed in claim 1, wherein each lapping guide has a plurality of portions including said guide arm, said portions being located in one plane so that said lapping guide is a flat integral member.

15 26. A knitting mechanism as claimed in claim 25, wherein said lapping guides are stamped out of a metal sheet.

27. A knitting mechanism as claimed in claim 25, wherein said eyelet is a slot at the free end of said guide arm.

20 28. A knitting mechanism as claimed in claim 1, wherein said cross bar is stationarily mounted on said machine; wherein said machine includes a reed movable between a rear position and a beat up position; and wherein said operating means move said knitting needles to said rear positions at a phase shift relative to the movement of said reed out of said beat up position so that said knitting needles enter the shed prior to the movement of said reed out of said beat up position.

30 29. A knitting mechanism as claimed in claim 1, wherein each lapping guide has a stem passing through said warp in open shed said position turnable between adjacent warp threads and having a journal end portion mounted in a bearing formed in said cross bar, and a radial guide arm angularly displacable in the open shed.
